UNITED STATES PATENT OFFICE

2,590,858

ROTATABLE TRIGGER GUARD FOR FIREARMS

Earle M. Harvey, Agawam, Mass., assignor to the United States of America as represented by the Secretary of War

Application April 28, 1949, Serial No. 90,214

3 Claims. (Cl. 42—69)

(Granted under the act of March 3, 1883, as amended April 30, 1928; 370 O. G. 757)

1

The invention described herein may be manufactured and used by or for the Government for governmental purposes without the payment of any royalty thereon.

This invention relates to trigger guards for firearms and more particularly to a construction wherein the trigger guard can be rotated laterally with respect to the longitudinal axis of the firearm.

It has been determined that heavy fingerless mittens afford the greatest degree of protection to the hands in extremely cold arctic weather. The use of such handgear, however, introduces difficulty in manipulating the triggers found in firearms having the conventional fixed trigger guard.

Attempts to provide suitable means for overcoming such difficulty have heretofore consisted in the attachment of an additional assembly designed to be carried separately from the gun. The utility of such separate devices was limited in practice by accidental loss, damage, or by being deliberately discarded to reduce the weight load carried by the individual soldier.

Accordingly, it is an object of this invention to provide means for exposing a firearm trigger by moving the trigger guard associated therewith out of its normal trigger-protecting position.

It is a further object of this invention to provide means for locking a swinging trigger guard in either a trigger-exposing position or in a conventional trigger-protecting position.

It is still another object of this invention to provide a trigger guard capable of being rotated to a trigger-exposing position and yet lie within the vertical plane formed by the sides of the weapon.

The specific nature of the invention as well as other objects and advantages thereof will clearly appear from a description of a preferred embodiment as shown in the accompanying drawings in which:

Fig. 1 is a right side elevational view of the trigger guard in the conventional trigger-protecting position.

Fig. 2 is a perspective left side view of the trigger guard in the position shown in Fig. 1.

Fig. 3 is a perspective view showing the trigger guard rotated to the trigger-exposing position.

Fig. 4 is a perspective view showing the manner in which the trigger guard of this invention allows grasping of the trigger when a heavy fingerless mitten is worn.

Although here shown in connection with a firearm of the type disclosed in my copending

2

patent application Serial No. 75,291 dated February 11, 1949, it should be understood that the trigger guard construction of this invention is equally applicable to any firearm provided with a conventional trigger and trigger guard.

There is shown in Fig. 1, a trigger housing 5 having a trigger 6 pivotally pinned thereto, and a trigger guard 8 rotatably secured to housing 5 in a manner to be explained.

The bottom portion of trigger housing 5 is provided with an arcuately shaped opening 9 into which the finger-engaging portion of trigger 6 extends. Opening 9 forms a front and rear depending projection 10 and 11, respectively, in housing 5. A longitudinally extending boss 12 is integrally formed on the left side of rear projection 11 and a slot 13 extends transversely through both boss 12 and projection 11. Boss 12 is provided with a hole 14 therethrough in which a pin 15 is fixedly secured by any suitable means. A rectangular rib 16 extends transversely along the front of projection 10.

Trigger guard 8 is of conventional shape and is rotatably secured at its front end to housing 5 by means of a pin 17 which extends through front projection 10 and through the left end of transverse rib 16 thereon. The rear end of trigger guard 8 is formed with an upstanding rectangular plate 18 which extends into slot 13 and is rotatably secured therein by means of pin 15. A spring 19 surrounds pin 15 and is located in abutting relationship between plate 18 and the front face of slot 13. The front end of trigger guard 8 is provided with a rectangular transverse groove 20 which is arranged to cooperate with rib 16 on housing 5.

In the conventional position of trigger guard 8 illustrated in Figs. 1 and 2, groove 20 at the front end thereof engages rib 16 and is locked thereto through the action of spring 19 which biases guard 8 rearwardly. However, when the operator is wearing heavy fingerless mittens or is unable for some other reason to conveniently grasp trigger 6, guard 8 may be rotated out of the way of trigger 6. To accomplish such rotation, guard 8 is first pushed forwardly against the bias of spring 19 to disengage groove 20 from rib 16. Then by swinging trigger guard 8 to the left, it can be rotated for approximately 180 degrees at which time groove 20 once again engages rib 16 and is locked thereto as a result of the bias of spring 19. In this rotated position as shown in Fig. 3, the outline of the inside surface of guard 8 is aligned with and adjacent to the arcuate surface of opening 9.

thereby permitting easy access to trigger 6. Furthermore, as a result of the 180 degree rotation, trigger guard 8 does not protrude beyond the sides of the firearm and consequently is not subject to damage in the event of accidental dropping or other rough handling. A hole is provided in guard 8, as shown at 21, for the insertion of a suitable tool or the tip of a cartridge in order to facilitate the forward pushing movement required to disengage trigger guard groove 20 from trigger housing rib 16. To return guard 8 to its conventional position, it is merely necessary to proceed in the manner above described except that rotation will be from left to right.

Thus there is here provided simple yet positive means for rotating a trigger guard out of the way of a trigger so that the latter may be grasped even though the operator of the firearm is wearing heavy fingerless mittens. Moreover, the construction of this invention is such that the trigger guard is automatically locked in either the conventional trigger-protecting position or the rotated position.

I claim:

1. In a firearm having a trigger and a trigger housing, the latter being provided with an arcuate opening at the bottom thereof into which the finger-engaging portion of the trigger extends, the combination of, an arcuate trigger guard having upwardly extending front and rear end portions rotatably secured to the trigger housing and arranged to straddle the arcuate opening therein, said trigger guard being thereby mounted for 180 degree movement between a trigger-protecting position wherein the inner surface of said trigger guard is diametrically opposed to the arcuate surface of the opening in the trigger housing and a trigger-exposing position wherein the inner surface of said trigger guard is parallel with and adjacent to the arcuate surface of the opening in the trigger housing, said trigger guard in either of said two positions arranged to lie within the outline formed by the sides of the firearm, means on the trigger housing and on said trigger guard arranged for cooperating engagement when said trigger guard is in either of said two positions, and resilient means for biasing said trigger guard rearwardly into said cooperating engagement with the trigger housing.

2. In a firearm having a trigger, the combination of, a trigger housing having an arcuate opening in the underside thereof for exposing the lower end of the trigger, a substantially arcuate trigger guard normally arranged to complete said trigger housing opening so as to encircle the trigger, said trigger housing having

a transverse slot rearwardly of said opening and a transverse rib forwardly thereof, said trigger guard having an upstanding rear end portion arranged to extend into said trigger housing slot and an upstanding front end portion having a transverse groove therein arranged to engage said trigger housing rib upon alignment therewith, pin means for rotatably securing said trigger guard to said trigger housing for lateral 180° movement between a trigger-protecting position and a trigger-exposing position, and resilient means between the front wall of said trigger housing slot and the inner face of said upstanding rear end portion of said trigger guard for automatically biasing said trigger guard groove into engagement with said trigger housing rib upon occurrence of said alignment therewith to lock said trigger guard to said trigger housing in either of said two positions.

3. In a firearm having a trigger housing and a pivotal trigger depending therefrom, the combination of an arcuate trigger guard having upwardly extending front and rear end portions, pin means for rotatably securing said portions and thereby said trigger guard to the underside of the trigger housing for lateral swinging movement about an axis parallel to the longitudinal axis of the firearm, said trigger guard being thereby mounted for rotation between a conventional trigger-protecting position wherein said trigger guard extends around and beneath the trigger and a trigger-exposing position wherein said trigger guard is reversed 180° thereby permitting unobstructed access to the trigger from the underside of the firearm, said pin means cooperating with said trigger guard to permit longitudinal sliding movement thereof relative to the trigger housing, said trigger guard front end portion having a transverse groove therein, a transverse rib on the trigger housing arranged for mating engagement in said trigger guard groove, and resilient means urging said trigger guard rearwardly whereby said groove therein engages with said trigger housing rib to releasably lock said trigger guard in either of said two positions.
